TONSORIAL DEVICE

Neil Helsclaw, Chicago, Ill., assignor of one-half
to Fred E. Sudlow, Rock Island, Ill.

Application April 17, 1946, Serial No. 662,714

4 Claims. (Cl. 30—213)

1

This invention relates to improvements in hair-cutting devices and more particularly to an implement having all the features of a hair clipper, a comb and a pair of shears embodied in a unitary device, all in cooperative relationship to each other. This application is an improvement of my copending applications Serial No. 576,795, filed February 8, 1945, now Patent 2,409,281, granted October 15, 1946, for Tonsorial device; Serial No. 658,551, filed March 30, 1946, for Tonsorial device; Serial No. 659,581, filed April 4, 1946, for Tonsorial device; and Serial No. 662,715, filed April 17, 1946, for Tonsorial device.

When cutting a head of hair, normally a pair of scissors, a hair clipper, and a comb are used to do the job. The comb must be used when either the clipper or the scissors is used; therefore, to do the job both hands of the hair cutter must be used at all times. The comb is normally used to lift the hair to a desired length, then the hair is cut over the comb either with a pair of shears or a clipper.

It is the main object of this invention to combine all of these tools in one implement and to produce a device which is far superior to known devices; to provide such a device which is so simple that any one can cut his own head of hair without having developed the skill or having the knowledge of hair-cutting; to provide in such a device a pair of movable clipper members which may be reversed at the will of the operator, on a guide bar, thereby producing a tool which may be used efficiently with either the left or right-hand of the operator.

Other objects of this invention are to provide a new and improved tool which may be used either as a clipper, a comb or a shears, all three being combined in a unitary structure; to provide a device of this character having a pair of transposable elongated toothed cutter members, one member arranged to be reciprocated by manipulation of a handle member; to provide a device of this character having a resilient plate member to retain the cutter members in assembled face to face relationship; to provide a device of this character having a pair of handles, one stationary and one movable; to provide a device of this character having a movable link arm and a stationary stop arm; to provide a device of this character having a movable link arm one end thereof pivotally secured to the movable cutter member whereby the movable cutter member is caused to reciprocate upon manipulation of the movable handle; to provide a device of this character having a slotted guide bar; to provide a device of

2

this character having a movable and a stationary handle joined together by a common pivot, the axis thereof being above the center line of the device whereby a push-pull movement is developed upon manipulation of the movable handle; to provide a device of this character having a guide bar with an endwise slot therein and provided with an off-set disc at the other end thereof; to provide a device of this character having link arms positioned in an end slot of the guide bar and adapted to bear against the guide bar; to provide a device of this character having link arms adapted to embrace the slotted ends of the guide bar; to provide cutter members in a device of this character which are removable from the driving mechanism and readily replaceable thereon at the will of the operator; and to provide a device of this character which is simple in construction and operation and relatively inexpensive to manufacture.

A specific embodiment of this invention is shown in the accompanying drawings wherein:

Figure 1 is a side elevational view of my invention.

Fig. 2 is a side elevational view of the inner face of the stationary cutter member.

Fig. 3 is a side elevational view of the guide bar.

Fig. 4 is a cross sectional view taken on line 4—4 of Fig. 1.

Fig. 5 is an end view of the link arm and stop arm in position on the guide bar, the guide bar being shown in cross section.

Fig. 6 is a perspective view of the movable link arm.

Fig. 7 is a perspective view of the stationary stop arm.

Fig. 8 is a top elevational view of my invention.

Fig. 9 is an end view of the cutter members taken on line 9—9 of Fig. 1.

Fig. 10 is an enlarged sectional view taken on line 10—10 of Fig. 1.

Referring in detail to the drawings, the movable handle member 1 and the stationary handle 2 are provided with offset hubs 1.1 and 2.1 respectively at their forward ends and are pivotally secured together by a bolt 3 extending through the hubs 1.1 and 2.1. Bolt 3 acts as a pivot on which the handle member moves and is positioned above the main longitudinal axis of the device to impart push-pull movement to the cutter members, upon manipulation of handle member 1.

The flat stationary guide bar is slotted on one end to form a slideway or slot 4 and hence provides horizontally disposed arms 5 and 5.1, the

latter with a stop or holding notch 5.2 and a vertically extending bore 5.3. The other end of the guide bar is provided with a circular offset washer-like base or disc 6 having a relatively large bore 7 therein, an aperture 8 and a countersunk bore 9.

The disc 6 of the guide bar is positioned between the hubs 1.1 and 2.1 of the handle members 1 and 2 respectively and is held therebetween by a bolt 3 which is threaded through the aperture 8, and a rivet 9.1 threaded through the countersunk bore 9 and seated in a suitable bore in the stationary hub 2.1 (see Fig. 4).

A movable link arm 10 is provided with a guiding collar 11 adapted to fit freely on arm 5 of the guide bar. The rear end of the link arm 10 is provided with upstanding bosses or ears 10.1 and 10.2, each having anchoring apertures 12 therein. The forward end of link arm 10 is provided with upstanding fingers 13. The link arm 10 is adapted to lie in slot 4 and abut against the inner face of the arm 5 of the guide bar and to be slideable thereon and within the slot 4. The fingers 13 are adapted to straddle the arm 5.

The ears 10.1 and 10.2 of the link arm 10 are pivotally secured to the center of hub 1.1 of the movable handle member 1 by rivets 14, or the like, threaded through apertures 12, bore 7 and seated in aperture 14.1 of the hub 1.1 so as to impart reciprocating movement to the link arm 10 upon closing or opening of the handle 1.

It will be apparent from Figs. 1 and 3 that the bore 7 is adapted to permit the pivoted rivet 14 to move freely forward or backward or in a slight arcuate movement when the handle 1 is alternately opened and closed.

Stop or anchoring arm 15, having a medially positioned collar 16, is adapted to fit within slot 4 and abut against the inner face of bar 5.1. The arm 15 is provided with an aperture 17 in the rear end thereof and a downwardly extending finger 18 integrally secured to the other end and extending across the width thereof.

The anchoring arm 15 is secured to arm 15.1 in any suitable manner, such as by rivet 19 threaded through aperture 17 and the bore 5.3 in the arm 5.1. The finger 18 seats in slot 5.2 of arm 5.1. A curved spring arm 20, also secured at one end by rivet 19 normally urges the link arm 10 and the anchoring arm 15 apart to cause the arms 10 and 15 to abut against the inner faces of the guide bar arm 5 and 5.1 respectively.

Referring to Fig. 1, it will now be apparent that when the handle 1 is moved downwardly toward the handle 2, the movement will cause the link arm 10 to shift to the left. When the handle is returned to its normal position the link arm will move to the right. As the handles are pivoted at a point above the center of the device the action on the center of the handle hubs, where the link arm 10 is anchored, will be of a push-pull type which will cause the link arm 10 to move forwardly and backwardly in a reciprocating movement when the handles are opened or closed.

The handle member 1 will automatically open or return to the position shown in full lines Fig. 1 by the action of the compression spring 21 which is secured to and between handle members 1 and 2 in any suitable manner.

The cutters or toothed members 22 and 23 are similar in design and construction, both having relatively long, slightly tapered teeth 24, so that when placed cutting face to cutting face, the composite structure thereof resembles a wide toothed comb. The members 22 and 23 are adapted to fit

one on each side of the guide bar and are each respectively provided with inwardly facing channels 25 and 26 whereby to form a slideway for the arms 5 and 5.1 of the guide bar and to position the members 22 and 23 cutting face to cutting face with respect to each other.

The toothed member 22 is provided with finger engaging recesses or seats 27 at both of its ends and bottom slideways or indentations 27.1 positioned below the seats 27. The toothed member 23 has the recesses and indentations oppositely arranged, i. e., the seats 27.2 being arranged adjacent the lower ends thereof while the slideways or indentations 27.3 are arranged thereabove. One of the engaging fingers 13 of the link arm 10 is seated in the seat 27 of the toothed member 22, while the other finger 13 merely moves freely along the slideway 27.3 of the cutter member 23. The securing finger 18 of the stop arm 15 is fitted into the recess 27.2 of the stationary cutter member 23 and the stop notch 5.2 in the guide arm, thereby preventing movement of the cutter member 23.

It will now be apparent that but one of the engaging fingers 13, positioned on the front end of the link arm 10, will fit into the engaging recess 27 of the movable cutter 22 the remaining finger, being positioned on the opposite side of the guide bar arm 5, will at all times merely abut against the slideway 27.3 of the stationary cutter 23. At the same time the finger 18 secured to the forward end of the arm 15 seats itself into the seat or notch 5.2 contained in the guide bar arm 5.1 and abut against the slideway 27.1 of the cutter member 22 and the engaging notch 27.2 contained in the now stationary cutter member 23. By this arrangement the bottom or stop arm 15 will hold and keep the cutter 23 immovable and will allow the cutter 22 to be moved by the link arm 10 when the handle member is depressed because one of the fingers 13 thereof will be positioned in the engaging recess or seat 27. The non-engaging finger 13 will slide freely in the slideway 27.3 of the cutter member 23.

Each toothed member 22 and 23 is provided with grooves 28, extending the length of the member and positioned adjacent the base line of the teeth 24, adapted to receive a plate spring 29 of inverted L-shape in cross section which is secured in position by passing a bolt 30 through an aperture 29.1 in the spring 29, through an aligned aperture 22.1 contained in the cutter member 22, through the slot 4 in the guide arm and anchoring the bolt to a suitably aligned and threaded aperture 31 contained in member 23.

The short arm 29.2 of the plate spring 29 seats in the groove 28 and the long arm thereof bears against the outer face of cutter member 22 adjacent the bottom end thereof only whereby substantially only the upper and lower edge of the plate spring 29 bear against the cutter member 22 leaving the major portion of the inner face of the spring 29 free of contact with the outer face of the cutter member 22, whereby equally applied tension is exerted to assure proper tensioning of the face of the cutter member 22 against the face of the cutter member 23.

It will now be apparent from the drawings and the foregoing description that the cutter members 22 and 23 are transferable from one side to the other of the guide bar. It will also be apparent from Figs. 9 and 10 that the cutter member against which spring plate 29 bears is the movable member whether it is on the right or left side of the guide bar, one of the teeth 12 of

the link arm 10 transmitting movement thereto while securing finger 18 of anchoring arm 15 will hold the other cutter member fast.

When it is desired to reverse the cutter members, the user grasps the collars 11 and 16 between his thumb and index finger and by pressing the two together the cutter members are freed from engagement with the link arms 10 and 15. By this operation, the finger 13 will be released from the seat 27 and the securing finger 18 will be released from the seat 27.2, thereby allowing the two cutter members to be withdrawn from the guide bar.

When assembled, the teeth 24 of both members 22 and 23 are in mutual alinement with each other; hence take on the appearance of a comb and thus may be used as such for combing the hair. When making a cut, the hair is first combed downwardly in the direction of the shoulders to straighten the same, then the device is moved in the opposite direction to lift the hair away from the scalp and outwardly to the position desired, so that the user may cut off the amount of hair he wants, by compressing the handle 1. While the handle is still closed, the device is withdrawn from the head and the handle allowed to open by releasing the pressure of the fingers and allowing the spring 21 to force the handle outwardly. Now the hair is again "combed" with the device to straighten the hair and the cutting step is repeated.

It is, therefore, apparent that this device does the work of the usual clipper and comb and it performs the function of all three of these devices and is capable of being manipulated with one hand only.

The long teeth, like a comb, pick up the hair and hold it firmly and perfectly therebetween until the handle is closed to make the cut. As the teeth are long and sturdy, they allow the hair that has been previously cut by the device to fall through the openings between the teeth so that only the hair which is desired to be cut remains between the teeth for clipping.

It can readily be seen that by placing one of the outer faces of the cutter members flat against the neck or skin of the user, the device functions as a fine clipper.

It will be understood that numerous details of the invention herein shown and described may be altered or omitted without departing from the spirit of the invention as defined by the following claims.

I claim:

1. A device of the class described comprising a pair of cutter members, one of said members being stationary and the other movable with respect thereto, each having elongated toothed members spaced closely together, a pair of handle members, one of said handle members being stationary and the other movable with respect thereto, offset hubs on the forward ends of each of said handle members, a stationary guide bar having an offset hub on one end thereof positioned between said handle members, and said guide bar extending forwardly of one of said handle members, a pivot bolt for securing said handle members and guide bar together and lying in a plane offset from the main longitudinal axis of said handles and guide bar, a link arm pivotally connected at one end to said movable handle, a spring stop arm rigidly secured at one end to said guide bar, said cutter members being positioned one on each side of the free end of said guide bar, the movable cutter member being op-

eratively and removably connected to said link arm and said stationary cutter member being removably secured to said spring stop arm, and resilient spring plate means for securing said cutter members to said guide bar in assembled face to face relationship, whereby when said movable handle is manipulated the movable cutter member will reciprocate.

2. The device according to claim 1, wherein each of said toothed members is provided with a horizontally extending channel on their inner faces for the reception of said guide bar, and spring means for insuring coactive engagement of said link arm and stop arm in operative position to said cutter members.

3. A device of the character described comprising a pair of handle members, one of said handle members being stationary and the other movable with respect thereto and each provided with

20 an offset hub, a common pivot bolt, the axis of which is above the longitudinal axis of the device as a whole, an elongated guide bar having a pair of horizontally disposed arms extending forwardly from said handles and having an offset hub on its rearward end, said hub on said

25 guide bar being secured between said handle hubs by said pivot bolt, a link arm slidably positioned on one of said guide bar arms and between both of said arms and having its rearward end pivotally secured to the hub of said movable

30 handle, a stop arm secured at one end to the other arm of said guide bar and between both of said arms, a spring positioned between said

35 guide bar arms to normally urge said stop arm and link arm apart, a pair of elongated cutter members having teeth of identical design ar- ranged one on each side of said guide bar, the free end of said link arm being removably se- cured to one of said cutter members, the other

40 cutter member being removably secured to the free end of said stop arm whereby upon manipulation of said movable handle the cutter member secured to said link arm will reciprocate while the other cutter member will remain sta- tionary in respect thereto, and spring plate

45 means for retaining said cutter member in as- sembled position on said guide bar in face to face relationship.

4. A device of the character described comprising a pair of handle members, one being sta- tionary and the other movable with respect thereto and each provided with an offset hub at its forward end; a common pivot bolt, the axis of which is above the longitudinal axis of

55 the device as a whole, an elongated guide bar having an offset hub on its rearmost end and having a pair of spaced horizontally disposed arms, one positioned above the other, extending forwardly from said hub, said hub on said guide

60 bar being secured between said handle hubs by said pivot bolt and having the bottom portion thereof integrally secured to the lower portion of said stationary handle hub by a rivet at a point diametrically opposite the said common

65 pivot bolt; a link arm having a pair of ears at its rear end, upstanding engaging fingers on its forward end and a guide collar intermediate of its ends, said link arm being slidably positioned on one of said guide bar arms and between both

70 of said arms and having the ears thereof pivot- ally secured to the hub of said movable handle; a stop arm provided with a downwardly extend- ing finger at its forward end, and a collar in- termediate of its ends, said stop arm being se- cured at its rear end to the other arm of said

guide bar and between both of said guide bar arms; a spring positioned between said guide bar arms to normally urge said stop arm and said link arm apart; a pair of elongated cutter members having teeth of identical design arranged one on each side of said guide bar in face to face relationship and one being movable with respect to the other, said handle members and said cutter members lying in the same longitudinal plane, said movable cutter member being provided with finger-receiving seats at either end thereof adjacent the base of the said teeth and having slideways at either end thereof below said finger-receiving seats, said stationary cutter provided with oppositely arranged slideways and seats, the former being above the latter, the fingers on the free end of said link arm being removably secured within said finger-receiving seats, the finger of said stop arm being remov-

ably secured within the seat contained in the stationary cutter whereby upon manipulation of said movable handle the cutter member secured to said link arm will reciprocate while the other cutter member will remain stationary in respect thereto; and spring plate means for retaining said cutter members in assembled position on said guide bar in face to face relationship.
